(57) CLAIM

The ornamental design for a sofa, as shown and described.

DESCRIPTION

FIG. 1 is a perspective view from the front side of a sofa in accordance with the present design;

FIG. 2 is a perspective view from the left side thereof; and,

FIG. 3 is a perspective view from the rear thereof.
The bottom of the sofa is not illustrated and forms no part of the present design.

1 Claim, 1 Drawing Sheet

FIG. 1

FIG. 2

FIG. 3
